CLAIM

The ornamental design for an elongated insert strip for adhesively fastening fabric to a frame, as shown and described.

DESCRIPTION

FIG. 1 is a perspective view of an elongated insert strip for adhesively fastening fabric to a frame, showing our new design;

FIG. 2 is an elevational view thereof, the opposite end being a mirror image;

FIG. 3 is a side elevational end view thereof, the opposite side being a mirror image, the elongated strip shown broken away to indicate indeterminate length;

FIG. 4 is a top plan view thereof; and,

FIG. 5 is a bottom plan view thereof.
